[57] CLAIM

The ornamental design for a bicycle or motorcycle handlebar grip, as shown and described.

DESCRIPTION

FIG. 1 is a perspective view of a bicycle or motorcycle handlebar grip showing my new design;

FIG. 2 is a side elevation view thereof, the opposite side being a mirror image of that shown;

FIG. 3 is an end elevation view thereof;

FIG. 4 is an opposite end elevation view thereof;

FIG. 5 is an enlarged fragmentary cross-sectional view thereof taken along line 5—5 in FIG. 2; and

FIG. 6 is a side elevation view of a bicycle or motorcycle handlebar grip showing a second embodiment of my new design, it being understood that opposite side is a mirror image of that shown and the end views are the same as the end views of the first embodiment shown in FIGS. 3 and 4.
